United States Patent Office

Des. 178,918
Patented Oct. 9, 1956

178,918

TOY SAVINGS BANK OR SIMILAR ARTICLE

Everett Cromwell English, New York, N. Y.

Application May 25, 1955, Serial No. 36,199

Term of patent 7 years

(Cl. D34—11)

Fig. 1.

Fig. 2.

Fig. 3.

Fig. 4.

Fig. 5.

Fig. 1 is a front elevational view of a toy savings bank or similar article, showing my new design;

Fig. 2 is a side elevational view thereof;

Fig. 3 is a rear elevational view thereof, showing the door in closed position;

Fig. 4 is a top plan view thereof; and

Fig. 5 is a rear perspective view thereof, showing the door in open position with one of the drawers partially withdrawn.

The captions are shown in dashed lines for illustrative purposes only.

I claim:

The ornamental design for a toy savings bank or similar article, as shown and described.
